UNITED STATES PATENT OFFICE.

CHARLES EDWARD HAVILAND, OF LIMOGES, FRANCE.

DESIGN FOR A PLATE OR LIKE ARTICLE.

SPECIFICATION forming part of Design No. 23,136, dated March 20, 1894.

Application filed February 15, 1894. Serial No. 500,312. Term of patent 14 years.

To all whom it may concern:

Be it known that I, CHARLES EDWARD HAVILAND, a citizen of the United States, residing at the city of Limoges, in the Republic of France, have invented and produced a new and original Design for a Plate and other Article, of which the following is a specification, reference being had to the accompanying drawings, forming part thereof, and in which—

Figure 1 is a top view of a plate bearing my design, and Fig. 2 is a section of same on the dotted line 2—2 of Fig. 1.

The leading features of my design consist of the ornamental configuration of the border for the outer edge of the rim of the plate, and the surface ornamentation on said rim.

In the drawings A designates the plate, and B the rim thereof, which rim has a scalloped outer edge both when viewed in plan, as shown in Fig. 1, and when observed at its side, as indicated in Fig. 2. Between the scallops a

forming the outer edge of the rim B are the slightly raised tapering portions b, the presence of which impart a distinctive ornate effect to the scallops a and render them discernible whether viewed in plan or at the edge of the rim, as shown. The rim B bears at intervals along its surface the ornate scroll figures C, the latter being in relief and extending on radial lines across the width of the said rim.

What I claim is—

The design for a plate or other article, substantially as shown and described.

Signed at the city of Limoges, in the Republic of France, this 10th day of January, A. D. 1894.

CHARLES EDWARD HAVILAND.
